UNITED STATES PATENT OFFICE.

GEORGE L. RICE, OF CHICAGO, ILLINOIS, ASSIGNOR, BY MESNE ASSIGNMENTS, TO INTERNATIONAL HARVESTER COMPANY, A CORPORATION OF NEW JERSEY.

TENSION DEVICE FOR WINDING AND REELING MACHINES.

1,385,925.

Specification of Letters Patent. Patented July 26, 1921.

Application filed February 1, 1918. Serial No. 214,960.

To all whom it may concern:

Be it known that I, GEORGE L. RICE, a citizen of the United States, residing at Chicago, in the county of Cook and State of Illinois, have invented certain new and useful Improvements in Tension Devices for Winding and Reeling Machines, of which the following is a full, clear, and exact specification.

- 10 My invention relates to tension devices for winding and reeling machines and more particularly to tension devices employed in connection with the supply bobbins from which the material is wound.
- 15 In winding and reeling machines where material is unwound from a bobbin, and is rewound in the shape of a ball, as, for instance, in the case of balling machines, it has been found necessary to decrease the tension
- 20 on the supply bobbin as the machine is started in order that the twine, yarn or other substance being unwound, may not be broken by the sudden starting of the machine.

It has also been found desirable to have a series of bobbins carried by a single reel, in order that time may not be lost in the operation of the machine when one bobbin runs out and another is required. In this connection it is necessary that means be provided for throwing the tensioning means out of operative position, and after a new bobbin is in place, for throwing the tensioning device into operative position. As this operation must be gone through with many times 35 in a day, the time consumed is considerable and it is of course desirable that this time be reduced to a minimum in order that the greatest possible amount of work may be accomplished by a single machine.

- 40 The object of the present invention is to enable the operator of the machine to lessen the tension on a supply bobbin during the starting of the machine, and to enable the operator to easily and quickly throw the tensioning means out of operation when it becomes necessary to replenish the supply of material.

With the above object in view, my invention consists in a tension device adapted to 50 coöperate with a supply member and in suitable means, such as gravity actuated means for maintaining the tension device in a plurality of positions, such as operative and inoperative positions. This device may be 55 manipulated, if desired, by any one of a

plurality of operating connections in such a manner as to enable the operator to control the position of the device from different locations with respect to the machine.

In the accompanying drawings I have 60 illustrated my invention in connection with the frame of a balling machine, the balling mechanism having been omitted, since it forms no part of the present invention. It should be understood that this tensioning 65 device is of general application and may be employed wherever it is desirable to lessen the tension during the starting of the machine, or to throw the tensioning device out of operation during the replenishing of the 70 supply of material.

In the accompanying drawings,

Figure 1 shows a front elevational view of my invention;

Fig. 2 shows a side elevation looking to- 75 ward the right in Fig. 1;

Fig. 3 is a side elevation similar to Fig. 2, showing the tensioning means thrown out of operation;

Fig. 4 is a partial side elevation on a small 80 scale, looking toward the left in Fig. 1; and showing the reel locking device;

Fig. 5 is a detail view showing the rotary reel structure;

Fig. 6 is an enlarged detail of the sup- 85 porting spindle for the bobbin, and

Fig. 7 is a detail view still further enlarged, showing the spring catch mechanism for holding the bobbin shaft in operative position.

The frame 10 of the balling machine has a rearwardly extending horizontal portion 11 which supports two upright standards 12 and 13, these standards having U-shaped upper ends 14, in which is secured the shaft 15 for the tensioning device. The standards 12 and 13 are provided intermediate their upper and lower ends with journals 16 for the shaft 17 on which is mounted the rotary reel 18 which carries the supply bobbins. This reel has a central sleeve 19, journaled on the shaft 17 and is provided at one end with radial arms 20, and at the opposite end with correspondingly located radial arms 21. The arms 20 have pivoted thereto 105 at their outer ends the bobbin supporting spindles 22, which are arranged as shown in Figs. 5 and 6, to be swung outwardly for the doffing of the empty bobbins and the reception of the full bobbin. The arms 21, as 110

illustrated in Fig. 5, are provided at their outer ends with sockets 23 which receive the bobbin spindles 22 when these spindles are in operative position on the reel.

5 In Fig. 7 I have illustrated a spring catch 24 for holding the spindle 22 in operative position. This catch is pivoted at 25 to the frame of the arm 21 and has a spring pressed 10 detent 26 which engages a pocket 27 on the frame of the arm 21 to hold the catch in closed position, thereby retaining the spindle in operative position.

In order to secure a reel against rotation when the material is being unwound from 15 the bobbins, I have provided a notched disk 28 which is secured to the reel shaft and rotates with the reel. This disk is provided on its periphery with notches 29 which are in substantial alinement with the reel arms. 20 Coöperating with these notches 29 is a pin 30 carried by an arm 31 pivoted at 32 to the standard 12. This pin rests in the notch and the weight of the arm with the engagement of the pin with the notch is sufficient 25 to prevent the reel from rotating until the arm 31 is lifted.

The tensioning means is embodied in a V-shaped brake device 33 which rests on the material carried by the upper bobbin and 30 this device as illustrated, comprises three flat blades, two of these blades being disposed on one side of the material and the third being disposed on the opposite side.

It will be understood that the number of 35 these blades is immaterial and that the device would operate successfully if a single blade constituted each portion of the V-shaped member. This tensioning brake device 33 is pivoted to arms 34 carried by a 40 sleeve 34 which is journaled on the shaft 15 above mentioned and forms a pivoted support for the brake. The shaft 15 has journaled thereon at one end a lever 35 and adjacent the lever 35 shaft 15 carries a sheave 45 36 and there is secured to this sheave on its periphery a chain 37 which is pivoted to a downwardly extending link 38. The lower end of this link is slotted as shown at 39 and this slot carries a pin 40 which in turn 50 is carried by a lever 41 at the rear end thereof. The opposite end of this lever is connected by a pin and slot connection to a lever 42 having a foot tread 43 at its opposite and front end. The lever 35 is secured by a bolt 55 or rivet 44 to the sheave 36 and to an extension 45 on the sleeve 34 carried by the shaft 15, and this sleeve carries on its opposite end a U-shaped extension 47 to which 60 is secured a triangular plate 48. This plate 48 is provided on its outer surface with a flat bearing portion or track 49 at the ends of which are disposed inwardly extending overhanging portions 50. A metallic strip or wire 51 is secured at its ends to these overhanging portions 50 and extends therebe-

tween. This track or bearing portion 49 carries a pin 52 having at one end a head 53 and secured at its opposite end to a downwardly extending rod 54. This rod carries at its lower end a nut 55 and a washer 56, and disposed above the washer is a spring 57 which forms a cushion for a weight 58 slidably mounted on the rod 54.

Having described the structure of the tensioning device, I will now describe briefly 75 the operation of the tensioning means as it is used on a reeling machine.

Assuming first that the rotary reel is in the position of adjustment shown in Fig. 2, and that the operator is about to start the machine,—by placing his foot on the tread 43 of the lever 42, a downward force is exerted on the chain 37 and rod 38, thereby rotating the sleeve 34 carrying the tensioning device 33 which is lifted sufficiently to 80 release the tension on the material being unwound, thereby enabling the operator to start the machine without breaking the material being unwound from the supply bobbin, but the action is such that sleeve 85 34 and plate 48 can not be rotated by the treadle 43 to a sufficient degree to cause weight 58 to slide in the track 49. After the bobbin from which the material is being unwound is emptied, the operator lifts the handle 35 thereby rotating the sleeve 34 on the shaft 15 and with the sleeve 34 the projection 47 and triangular plate 48 are rotated. When the lever 35 has been lifted sufficiently 90 and the plate 48 has been rotated about the shaft 15 beyond a certain degree the pin 52 and rod 54 carrying the weight 58 will slide on the track or bearing portion 49 and the weight will pull downwardly on the plate 48 and will assist in rotating the sleeve 34, 95 the final position of the parts above described being shown in Fig. 3. From the showing in Fig. 3 it will be clear that the weight 58 holds the tensioning device out of 100 operation until the operator swings the lever 35 in a downward direction, again rotating the plate 48 and sleeve 34 on the shaft 15. Thus it will be seen that the weight is utilized in maintaining the tensioning device in both extreme positions of its adjustment, as illustrated in Figs. 2 and 3. When 105 the tension device has been thrown out of operation as shown in Fig. 3, the operator lifts the handle and arm 31 and releases the reel, which may then be swung to such a position that a full bobbin is disposed uppermost. When this has been done the operator drops the arm 31 into position to hold the reel stationary and lowers the lever 35, placing the tensioning means in position on 110 the material of the full bobbin. The spindle carrying the empty bobbin is swung outwardly to the dotted line position shown in Figs. 5 and 6 after the catch 26 has been 115 withdrawn, and a full bobbin may be placed 120 on the spindle. The bobbin is then wound 125 on the reel and the tensioning means is withdrawn, the weight 58 being held in the track 49 by the projection 47. The operator then lifts the handle 35 and 130

in position on the spindle which will then be again swung inwardly and held in operative position by the catch. If the operator desires to throw the tensioning device 33 out of operation from the front of the machine, the levers 41 and 42 may be so proportioned that a downward pressure exerted on the tread 43 will rotate the sheave 36 and the sleeve 34 sufficiently to throw the plate 48 to such an extent that the weight 58 will complete its rotation to the position shown in Fig. 3. The main object, however, of the lever 42 and tread 43 is to enable the operator to temporarily lessen the tension on the supply bobbin during the starting of the machine.

Although I have in the above specification described one embodiment which my invention may assume, it should be understood that the device is capable of many modifications and that such modifications may be employed without departing from the spirit and scope of the invention as expressed by the following claims.

25 What I claim as new is:

1. In a winding and reeling machine, a rotatably supported bobbin, a tensioning brake having its pivot directly over said bobbin and having a pivoted support adjacent the bobbin and brake setting means connected to said pivoted support and shiftable from one side of the pivot of said support to the other for holding the brake either against or away from the bobbin.
- 35 2. In a winding and reeling machine, a rotatably supported bobbin, a tensioning brake having a pivoted support adjacent the bobbin, a member carried by the pivoted support and extending on opposite sides of its pivot and a weight carried by said member and shiftable from one end to the other thereof for holding the brake either against or away from the bobbin.
- 45 3. In a winding and reeling machine, a rotatably supported bobbin, a tensioning brake having a pivoted support adjacent the bobbin, a member provided with a lower portion secured to the pivoted support beneath its pivot and an upper portion extending on opposite sides above its pivot, and a weight carried by said upper portion and shiftable from one end to the other thereof when said pivoted support is rotated beyond a certain degree.

4. In a winding and reeling machine, a 55 rotatably supported bobbin, a tensioning brake having a pivoted support adjacent the bobbin, a member carried by the pivoted support and extending on opposite sides of its pivot, a weight carried on said member and shiftable from one end to the other thereof when said pivoted support is rotated beyond a certain degree and separate means for rotating said support within and beyond such degree. 60 65

5. In a winding and reeling machine, a frame, a rotatable supply member, an arm pivoted to said frame, a tension means on said arm, a plate operatively connected to said arm and having a track thereon, and 70 means carried by said track and adjustable thereon for holding said arm and tension means in operative and inoperative position and for assisting in one position of its movement in the rotation of said arm and 75 plate about their pivot.

6. In a winding and reeling machine, a frame, a rotary reel carried thereby, a plurality of rotatable supply members carried by said reel, and an arm carried by said frame, tension means carried by said arm and operatively associated with one of said supply members, a sleeve secured to said arm and rotatable with respect to said frame, a plate secured to said sleeve and 85 having a track, a pin mounted upon said track and movable with respect thereto, a rod carried by said pin, and a weight mounted on said rod. 80

7. In a winding and reeling machine, a 90 frame, a shaft carried thereby, a rotary reel mounted on said shaft, a plurality of rotatable supply bobbins carried by said reel, means for locking the reel with the upper bobbin in delivering position, an arm pivotally mounted on said frame, a tension member carried by said arm and adapted to engage the upper of said supply bobbins, and a sliding weight shiftable from one side of the pivot of said arm to the other for 100 holding said tension member in engagement with said supply bobbin during delivery and for holding said tension member out of engagement with said supply member during rotation of the reel. 95 105

In testimony whereof I affix my signature.

GEORGE L. RICE.
